COAT HANGER

Stuart L. Maxwell, 727 Dayton, Muskogee, Okla.
Filed Apr. 20, 1965, Ser. No. 449,458
1 Claim. (Cl. 223—91)

This invention relates to an improved garment hanger. More particularly, the invention relates to a garment hanger having the usual provision of an inverted V-shaped body portion for receiving a coat or jacket thereon and including an improved trouser hanger bar characterized by its simplicity, ease of use and effectiveness to prevent trousers from sliding off.

A garment or coat hanger is a common household item and its use is well known. Typically, a coat hanger consists of an inverted V-shaped upper portion designed to receive the shoulder portions of a coat or jacket and a lower crossbar particularly adapted, when the hanger is used for men's clothing, to receive trousers. One problem with the usual trouser portion of the hanger is that unless great care is exercised in draping trousers over the crossbar, one side or the other will be heavier and the trousers will slide off.

Others have proposed various means for preventing trousers from sliding off trouser crossbars and examples of efforts in this direction are found in the following U.S. Patents: 1,512,130; 1,895,695; 1,968,065; 2,044,346; 2,123,259; and 2,153,905.

Previous efforts to provide a satisfactory hanger for trousers have achieved varying degrees of success. However, this invention provides an improved garment hanger which provides means for hanging a coat plus accomplishing the additional objective of providing a greatly improved means of hanging trousers. While, as previously indicated, others have provided means of retaining trousers of the trouser bar of a coat hanger, this invention is distinguished by a unique arrangement and manufacturing construction characterized by simplicity and economy by improved ease of use.

It is therefore an object of this invention to provide an improved garment hanger.

More particularly, an object of this invention is to provide a garment hanger having the usual inverted V-shaped body portion for hanging a coat thereon and including a highly improved trouser crossbar portion having improved means of preventing trousers hung thereon from sliding off.

Another object of this invention is to provide an improved garment hanger having the usual inverted V-shaped body portion to receive a coat thereon plus an improved trouser crossbar portion, the improved crossbar portion being characterized by a construction arrangement utilizing single lengths of paralleled small diameter metal bars for a plurality of purposes. A better understanding of the invention which fulfills these and other objects will be had by referring to the following description and claim, taken in conjunction with the attached drawings, in which:

FIGURE 1 is an elevational front view of the hanger of this invention.

FIGURE 2 is a cross-sectional view of the hanger of this invention.

FIGURE 3 is a cross-sectional view taken along the line 3—3 of FIGURE 2.

FIGURE 4 is a cross-sectional view of the trouser crossbar portion of the hanger as taken along the line 4—4 of FIGURE 2.

FIGURE 5 is a cross-sectional view taken along the line 5—5 of FIGURE 2 showing the method of forming the trouser crossbar hinge.

FIGURE 6 is a cross-sectional view taken along the

2

line 6—6 of FIGURE 2 and further showing the method of forming the trouser crossbar hinge.

This invention may be described as an improved garment hanger. More particularly, but not by way of limitation, the invention may be described as an improved garment hanger comprising a body having extending arm portions forming an inverted obtuse V, each of the arm portions terminating at the outer end with a downwardly extending portion, such downwardly extending portions defining first and second vertical portions, an upwardly extending hanger hook affixed to said body at the apex, a trouser receiving crossbar, means hingeably affixing said crossbar at one end to the first of said vertical body portions, a crossbar hook affixed to the second of said vertical body portions removably receiving the other end of said crossbar, and spaced paralleled trouser holding rods extending from the first to the second vertical body portion, said trouser holding rods closely spaced above and parallel to said trouser crossbar.

Referring now to the drawings and first to FIGURE 1, the hanger of this invention is shown in elevational side view. The hanger consists of two basic portions, that is, a body portion generally indicated by the numeral 10 and a trouser crossbar generally indicated by the numeral 12. The body portion 10 consists of two extending arm portions 14 and 16 which form an inverted obtuse V. Each of the arm portions terminates at the outer end with a downwardly extending portion defining a first and second vertical portion 18 and 20.

Affixed to and extending upwardly from the body portion 10 at the V apex of the arms 14 and 16 is a hanger hook 22 whereby the garment hanger may be hung on a closet rod or the like.

The trouser crossbar 12 consists basically of a trouser crossbar 24 having means generally indicated by the numeral 26 hinging the bar at one end to first vertical body portion 18. The hinging means 26 will be described in detail subsequently. The opposite end of the crossbar 24 is removably supported by a crossbar hook 28 which extends downwardly from the second body vertical portion 20.

Referring to the FIGURES 2 through 6, all cross-sectional views, the details of construction of the improved trouser crossbar of the hanger of this invention are best shown. As shown in FIGURE 4 the crossbar 24 is preferably of a T-shaped cross-sectional configuration, that is, in cross-section the crossbar 24 has a vertical body portion 24A and an integral T-bar portion 24B. The preferred further arrangement of the cross-section of the trouser bar 24 is the provision wherein the T-bar portion 24B has an upper surface 24C configured substantially the segment of a circle. The preferred embodiment of the crossbar 24 as illustrated in FIGURE 4 readily adapts the crossbar to be constructed of extruded plastic, however, construction of wood or other similar materials is acceptable.

The most important part of this invention is the provision of spaced paralleled trouser holding rods 30 and 32. The rods 30 and 32 are preferably small diameter metallic rods and preferably formed of bendable wire. The trouser holding rods are parallel to each other, spaced from each other, extend horizontally between the body vertical portions 18 and 20, and are positioned above and adjacent to the upper surface 24C of the trouser crossbar 24. When no trousers are positioned on the trouser crossbar 24, the trouser holding rods 30 and 32 may be in contact with it, but they are resiliently extended upward when trousers are placed across the bar 24 and the bar placed in position on hook 28.

The purpose of the trouser holding rods 30 and 32 is to prevent trousers placed upon the trouser crossbar 24 from slipping off. When it is desired to place trousers

upon the hanger the end of the crossbar 24 is removed from hook 28 by a slight upward and lateral movement. Trousers can then be easily slipped on to the bar 24 and the bar then placed within and received by hook 28. The construction of hook 28 is best shown in FIGURE 3.

An important part of this invention is the configuration of the trouser holding rods 30 and 32 which are arranged in such a way that these rods serve three separate and distinct functions. As shown in FIGURES 1, 2, 5 and 6, the trouser holding rods 30 and 32 are configured to form the hinge means generally indicated by the numeral 26. As shown in these views the paralleled rods are each bent adjacent one end thereof at substantially a right angle, the right angle being indicated by the numeral 34. The right angle 34 bent in each of the rods 30 and 32 forms a downwardly extending vertical portion 36, which portion extends downwardly beyond the end of the first vertical body portion 18. The body portion 18 encompasses the angular portions 34 of rods 30 and 32. Secured to the downwardly extending portions 36 of rods 30 and 32 is the trouser crossbar 24. In this manner the downwardly extending portions 36 of rods 30 and 32 constitutes the hinge means 26 by which the trouser bar 24 is hingeably affixed to the first vertical body portion 18.

As is best seen in FIGURES 1, 2 and 3, the opposite end of one of the trouser holding rods 30 is bent at an angle 38, the angular portion being received by second vertical body portion 20, and extends downwardly from such vertical body portions to form the previously mentioned hook 28.

In this manner it can be seen that the trouser holding rods 30 and 32 each perform triple functions, that is, (1) the parallel horizontal spaced rods serve to maintain trousers draped across the trouser crossbar 24 in place and prevent the trousers from slipping off the hanger; (2) the integral downwardly extending portions 36 provide the hinge means by which the trouser bar 24 is supported to the hanger; and (3) the integral downwardly extending portion at the opposite end forms the trouser bar receiving hook 28.

As shown in FIGURE 5 the downwardly extending portions 36 of the trouser holding rods is formed in a U so that in essence the trouser holding rods 30 and 32 are a single length of wire which performs the three functions above enumerated. This arrangement is optional as the hanger can equally be constructed wherein the point A indicated in FIGURE 5 may be separated so that two lengths of wire are utilized to form the three functions.

The body portion of this invention, while it can be made of a variety of materials, is preferably formed of plastic. During manufacturing processes the angular portions 34 and 38 of the trouser holding rods 30 and 32 are embedded in the vertical body portions 18 and 20. In like manner, the crossbar 24 may be manufactured in a way so that the downwardly extending portions 36 of the trouser holding rods 30 and 32 are embedded into the end of the bar as it is formed.

The hinge 26 formed by downwardly extending portions 36 of rods 30 and 32 is a hinge in a limited sense, that the hinge permits the trouser crossbar 24 to be moved sufficiently to hook and unhook the end from hook 28. When unhooked from hook 28 the trouser crossbar 24 extends normally horizontally with the end opposite hinge 26 just below hook 28. This permits a user to easily slip trousers over the trouser crossbar 24 with one hand while

the hanger is held by the other hand grasping arm portion 14.

The hanger of this invention is simple of construction, economical to manufacture and provides an improved garment hanger having superior means of retaining trousers on the trouser crossbar so that the possibility of the trouser slipping from the bar is eliminated.

While the invention has been described with a certain degree of particularity, it is manifest that many changes may be made in the details of construction and arrangement of components without departing from the spirit and the scope of this disclosure.

What is claimed:

An improved garment hanger comprising:
 a body having extending arm portions forming an inverted obtuse V, each of the arm portions terminating at the outer end with a downwardly extending portion, the downwardly extending portions defining first and second vertical portions;
 an upwardly extending hanger hook affixed to said body at the V apex;
 spaced paralleled rods each bent at one end at a right angle forming paralleled downwardly extending portions, one of said rods bent at the opposite end at a right angle forming a single downwardly extending portion, the portions of said rods forming said right angles encompassed within the lower end portions of said first and second vertical portions whereby said parallel rods extend horizontally between said first and second vertical portions, said parallel downwardly extending portions of said rods extend downwardly from the lower end of the first vertical portion, the single rod portion extending downwardly from said second vertical body portion and bent to form a crossbar hook; and
 a crossbar having a first end affixed to said parallel downwardly extending portions of said rods extending from said first vertical body portion, said paralleled downwardly extending portions of said rod forming a hinge permitting limited hingeable movement of said crossbar, said crossbar being of T-shaped cross-sectional configuration having an integral horizontal and vertical portion, the horizontal portion being adjacent, parallel and below said paralleled rods and having an upper surface defined substantially as a segment of a circle, the second end of said crossbar being removably received and supported by said crossbar hook.
